WAVE MODULATION

Karl Fritz, Berlin, Germany, assignor to Telefunken Gesellschaft für Drahtlose Telegraphie m. b. H., Berlin Germany, a corporation of Germany

Application January 8, 1936, Serial No. 58,066
In Germany February 25, 1935

2 Claims. (Cl. 250—17)

This invention is concerned with an arrangement to modulate electromagnetic waves or oscillations which operates in such a way that the action brought upon the oscillations takes place 5 outside the oscillator or wave generator.

In my United States appln. Ser. No. 58,067, filed Jan. 8, 1936, which corresponds to German appn. Ser. No. T44,903 VIIIa/21a4, a modulation method has been disclosed which may be called 10 reflection modulation. Briefly speaking, the same consists in that the transmission line which connects the wave generator, which may be a transmitter, with the consumer, which may be a radiator, is bridged at a definite point, whose position 15 is readily ascertainable tentatively or experimentally, by a non-reactive resistance or preferably an impedance whose value varies as a function of the modulation process. If the said impedance is of an infinitely large value, it will 20 exercise no influence at all upon the energy transfer, and the oscillations will reach the radiator in undiminished form. If the impedance is reduced, then the characteristic impedance of the transmission line at the place where the modulation 25 device is mounted, will be altered unsteadily by great amounts, and this causes, in accordance with known laws, a partial reflection of the oscillatory energy. As a result, much of the energy is used up and only part of the oscillations reach 30 the radiator. It is also feasible to produce this modulation by reflection about mean or average impedance values if the modulation impedance is set to a definite static value, and this value then increased and decreased above and below the 35 said definite means static value. It has also been shown in the prior application that it is possible, by the ways and means disclosed, to insure energy distribution between two consumers or radiators, the transmitter then operating with adjustable 40 or regulable power, one of the consumers or loads being fed with energy which is not allowed to be passed to the other consumer. The two consumers may, for instance, consist of two antennae with different directions of radiation or dissimilar 45 polarity. Control of energy is effected by a pair of modulation means co-ordinated to each radiator and worked in phase opposition (push-pull). The signals issuing from the two radiators, as will 50 thus be seen, differ only by a phase displacement angle of 180 degrees, while otherwise they are perfectly identical.

Now, according to the present invention, ways and means are disclosed whereby two or more radiators fed from one and the same wave generator are caused to radiate different signals 55

which are totally independent of one another. This is accomplished by co-ordinating a modulator with each radiator. The position of the modulator in the line, e. g. its distance from the radiator and wave oscillator, is so chosen that it 5 will act upon only the passage of oscillatory energy from the generator to the radiator with which it is co-ordinated, and will not react upon the other radiators.

The idea underlying the invention will be explained in more detail below by reference to the annexed drawing, in which the Figures 1 and 2 illustrate transmitters with two radiators and separate modulators for each radiator. Referring to the drawing, S designates a transmitter which 10 will be assumed to generate an ultra-short wave (decimeter wave). This wave is carried over an energy feed lead or download E consisting, say, of a parallel-wire system, to two radiators A₁, A₂. Modulation is to be effected by two devices 15 M₁, M₂ which may assume any of the forms described in the application referred to above, such as condensers comprising vibratory electrodes, discharge paths in high vacua or in rare-gas atmospheres, etc. As has been ascertained from 20 practical experiments, it is possible to find such values for the distances a, b, between the wave generator and the radiators and modulation devices, respectively, that the modulator means M₁ will exercise a control action only upon the 25 energy flow to the radiator A₁, while producing no effect upon the feed of the radiator A₂. The same thing applies similarly to the modulator M₂. The explanation for this behavior probably 30 is this, that the two modulators have such a relative position that they form a nodal point only for the reflux of energy. The result of this circumstance is that the two modulator devices are 35 perfectly uncoupled or neutralized in reference to the radiator that does not respectively belong 40 to them. It will be understood that in a similar way also three or more radiators could be operated by a corresponding number of modulation means.

Inasmuch as the position of the modulators 45 upon the energy feed lead is associated with the length of the working wave, there results the necessity to shift the position of the modulators whenever there is a change in wave-length. In order to facilitate this manipulation, it is preferable to establish coupling by positively acting 50 means (inter-locking) between the tuning means C of the wave generator S and the means for adjusting the modulating devices along the lines. This may be accomplished, for instance, as shown 55

in Fig. 2 by connecting the control shaft of C with a gear 8 driven by a rack 10, which also shifts the modulators M₁, M₂ along the lines. I may use any other suitable gearing. However, 5 the same problem is solvable by still simpler ways and means by changing not only the geometric, but also the electric position of the modulation means. As has been indicated in the parent patent application it is possible to insert 10 variable capacities along the feed lead or down-lead, or to bridge the latter by capacities or inductances, so that the electrically active length of the lead section thus affected will differ from the geometric position. It is evident that the 15 setting of a variable condenser is more easily accomplishable and capable of being coupled or interlocked with the adjustment of the transmitter than a geometric shift of the modulator.

The object of the application is of considerable 20 practical value in all such instances where it is necessary to send several communications on one and the same wave. An instance that may be cited here is the formation of a guide-ray or beam obtained by superposing two dissimilarly 25 modulated directional radiations of equal frequency.

What is claimed is:

1. In a signalling system a tunable oscillation generator, a plurality of radiators, a separate feed line comprising two leads connecting each radiator to said generator, a separate modulating means adjustably connected to each line, and means for simultaneously tuning said generator and adjusting the position of said modulating means along said lines. 5

2. In a system for modulating high frequency oscillations in accordance with a plurality of signals, a source of high frequency oscillations, a plurality of radiators, a feeder system comprising a common portion and two branches connecting said source of oscillations to said radiators, and separate modulating means which may be actuated in accordance with signals shunting the branch portions of said feeder system, said separate modulating means shunting said branch portions of said feeder system being located at 20 points on the respective branch circuits such that operation of one of said modulating means has no effect on the energy in the branch circuit to which the other modulating means is connected. 25
